This patent relates to a device for holding a blouse in its proper position inside a skirt. It is particularly designed to be attached to the inside of the waistband of a skirt and to engage with the fabric of a blouse to prevent the blouse from working itself out of the skirt as a result of movements of the person wearing it.

BLOUSE ANCHOR

Doris Jane Hennie, Little Falls, N. J.

Application December 17, 1947, Serial No. 792,165

5 Claims. (Cl. 2—323)

1

This invention is directed to the provision of an improved blouse anchor for attachment to the inside of the waistband of a skirt and for detachable engagement with the fabric of a blouse to prevent the blouse from working itself out of the skirt as a result of movements of the person wearing it.

The improved blouse anchor comprises a thin, flat, substantially rigid member configured to define a centrally located vertical wedge slot for detachable engagement with a blouse, and formed also with a pair of openings located one on each side of the wedge slot. A pair of elastic tapes are secured to said member by being passed one through each of said openings, and by each being doubled back on itself. The tapes each extend out horizontally in a direction away from the central slot. In use, the ends of the tapes are secured to the inside of a skirt adjacent its waistband but far enough below the upper edge of the waistband so that the anchor is concealed. The tapes should be drawn taut along the waistband, but should not normally be under any substantial degree of elastic tension.

By engaging the wedge slot of the anchor with the fabric of a blouse, the blouse is prevented from climbing out of the skirt. The elastic tapes of the blouse anchor, by which it is secured to the skirt, allow substantial relative movement between the skirt and the blouse, so that the movements of the wearer are not hampered; but whenever the blouse tends to work its way upward and out of the skirt, it is urged down again by the anchor to its proper position. Generally two such anchors, located one on each side of the skirt, are all that are required to retain the blouse inside the skirt all around the wearer's waist.

Preferred embodiments of the invention are described below with reference to the accompanying drawings, in which

Fig. 1 is a projection of one form of blouse anchor made from wire in accordance with the invention;

Fig. 2 is a view showing how the new blouse anchor is fastened to a skirt and engaged with a blouse; and

Fig. 3 is a plan of another form of blouse anchor, made from sheet material.

The blouse anchor shown in Fig. 1 comprises a stiff, smooth-surfaced wire 5 of steel, nickel-plated brass, or other suitable material, bent virtually double at its midpoint 6 to form a centrally located, narrow, vertical wedge slot 7. Each end wire 8 of the wire is looped outwardly, up-

wardly and thence inwardly to form a pair of openings 9 on opposite sides of the slot 7. A pair of elastic tapes 10 are passed one through each opening, and each tape is doubled back on itself to secure it to the bent-wire element. The tapes extend horizontally, at right angles to the vertical axis of the wedge slot, and outwardly therefrom.

In use, the ends 11 of the tapes 10 are sewn or otherwise fastened to the inside of a skirt 12, to, or adjacent to, its waistband 13, as shown in Fig. 2. The tapes should be drawn substantially taut when they are sewn in place, so as to lie flat against the inside of the skirt, but should not be under elastic tension to any substantial degree. When thus fastened in place, the new blouse anchor does not tend to produce either unsightly wrinkles or unsightly bulges in the skirt, and is perfectly comfortable to the wearer.

A small part 14 of the fabric of a blouse 15 is drawn into the wedge slot, and when thus engaged with the blouse anchor, the blouse is held from climbing out of the skirt. If movements of the wearer result in pulling the blouse upwardly, the elastic tapes yield to allow relative movement between blouse and skirt, without damaging either. However, when the force tending to pull the blouse up is released, the tapes draw it back into its proper position inside the skirt.

An alternative form of blouse anchor, made from fairly stiff, rigid sheet metal or sheet plastic material, is shown in Fig. 3. In this modification, a small rectangular member 16 of the sheet material is cut to form a narrow, central, vertical wedge slot 17 extending inwardly from the lower side edge of the member. A pair of vertical, elongated slot openings 18 are formed in the member at each side of the wedge slot, with their long axes substantially parallel to the axis 40 of the wedge slot. Elastic tapes 19 extending horizontally outwardly from the wedge slot, substantially at right angles thereto, are fastened to the sheet material element in the same manner as described in connection with Fig. 1, by being passed through the openings 18 and being doubled back on themselves. The top edge of the member 16 advantageously is bent over, or is otherwise stiffened, as indicated at 20, to reinforce the anchor. This modified form of blouse anchor is used in the same manner as the form shown in Fig. 1 and as described in connection with Fig. 3.

The new blouse anchor is simple and inexpensive to manufacture, and very easy to fasten in place. It has proven to be highly effective for holding a blouse in its proper position inside the

wearer's skirt. It is comfortable to wear, and does not damage either the skirt or the blouse. When properly mounted on the skirt it is fully concealed and does not reveal its presence by unsightly bulges or wrinkles. It may be secured in the skirt at the time the latter is made, or may be sewn in at a later time with but a few minutes work.

I claim:

1. The combination with a skirt of a blouse anchor for restraining a blouse being worn with the skirt from working itself out of the skirt, said anchor comprising a substantially rigid member configured to define a substantially centrally located vertically extending wedge slot for engagement with a blouse and having an opening on each side of said slot, a pair of elastic tapes extending one through each of said openings, each of said tapes being doubled back on itself with its ends drawn out horizontally in a direction away from said wedge slot, each tape being fastened adjacent its ends to the inside of the skirt adjacent the skirt waistband but far enough below the upper edge of said waistband so that the blouse anchor is concealed, the tapes being drawn out substantially taut without normally being under any substantial degree of elastic tension.
2. A blouse anchor of the character described comprising a thin flat substantially rigid member having therein a centrally located vertically extending wedge slot for engagement with the fabric of a blouse, and having an opening for receiving an elastic tape on each side of said slot, and a pair of elastic tapes secured to said member by being passed one through each of said openings and being doubled back on itself, said tapes each being arranged so as normally to ex-

tend horizontally in a direction away from said wedge slot.

3. A blouse anchor of the character described comprising a thin flat substantially rigid member configured to define a centrally located vertical wedge slot and having a pair of tape-receiving openings located one on each side of said wedge slot, and a pair of elastic tapes passed one through each of said openings and thereby secured to said member, the tapes extending horizontally each in a direction away from said slot.
4. A blouse anchor of the character described comprising a stiff smooth-surfaced wire bent substantially double adjacent its midpoint to form a wedge slot between the portions of the wire on opposite sides of the bend, the ends of the wire being looped outwardly and upwardly and thence inwardly to form a pair of openings on opposite sides of said wedge slot, and a pair of elastic tapes passed one through each of said openings and thereby secured to said bent wire element, the tapes each extending outwardly away from the wedge slot substantially at a right angle thereto.
5. A blouse anchor of the character described comprising a thin substantially rigid member of sheet material having a narrow centrally located wedge slot extending inwardly from an edge thereof, and having a pair of elongated openings formed therein on opposite sides of said wedge slot, the long axes of said openings being substantially parallel to the axis of the wedge slot, and a pair of elastic tapes passed one through each of said openings and being thereby secured to said member, the tapes each extending outwardly from the wedge slot substantially at a right angle thereto.

DORIS JANE HENNIE.
